DESIGN FOR A HAT

Bertha Marks, Lawrence, N. Y.

Application June 23, 1941, Serial No. 101,620

Term of patent 3½ years

To all whom it may concern:

Be it known that I, Bertha Marks, a citizen of the United States of America and a resident of the town of Lawrence, in the county of Nassau, State of New York, have invented a new, original, and ornamental Design for a Hat, of which the following is a specification, reference being had to the accompanying drawing, forming a part thereof.

Fig. 1 is a top view of a hat showing my new design.

Fig. 2 is a bottom perspective view thereof.

Fig. 3 is a side view thereof.

I claim:

The ornamental design for a hat, substantially as shown.

BERTHA MARKS.
